METALLO-ORGANIC COMPOUND AND
METHOD OF PREPARING THE SAME

George H. Denison, Jr., Berkeley, and Arthur C. Ettling, Richmond, Calif., assignors to Standard Oil Company of California, San Francisco, Calif., a corporation of Delaware

No Drawing. Application May 21, 1940.
Serial No. 336,392

11 Claims. (Cl. 260—619)

This invention relates to methods of preparing metal compounds of organic acids and involves, as a preferred group, the preparation of metal salts of high molecular weight organic acids.

Methods utilized heretofore in the preparation of metal salts of high molecular weight organic acids have involved various difficulties. This is particularly true where metal salts of relatively weak bases, such as the alkaline earth metals and/or high molecular weight water-insoluble organic acids, are involved. Often expensive raw materials have been required and extended purification methods were necessary to obtain the product of the desired purity and characteristics. For example, when salts of high molecular weight water-insoluble organic acids are prepared by double decomposition in the presence of an aqueous medium, various undesirable reaction products are sometimes separable only after extended washing or other purification steps.

Additional difficulties have been encountered where the metallic compound of the high molecular weight organic acids is amorphous or has a high melting point. It has been found, for instance, that when water is present during preparation of such compounds, the salts tend to hold the water so intimately that it can be subsequently removed only by heating to such high temperatures as will partially decompose or deteriorate the compound. The water formed by reaction of an hydroxide with an acidic hydrogen, as in some prior proposed methods of preparation, is found to introduce this difficulty and materially alter the solubility of the salt in organic solvents such as petroleum hydrocarbons. The amount of water necessary to materially alter the solubility or other properties of these compounds is, in some instances, quite small.

We have discovered that metal compounds of organic acids can be advantageously prepared by reacting, in a non-aqueous environment, a carbide of a metal and the organic acid. This process is particularly advantageous when applied to high molecular weight organic acids. Despite the fact that the high molecular weight organic acids are extremely weak and in general relatively unreactive, their metal salts have been obtained in an anhydrous and relatively pure condition. High yields of the desired compounds have been obtained by using relatively cheap raw materials where other processes either gave a less desirable product or required more expensive reagents as starting materials.

Accordingly, an object of the invention is to

provide an improved method of preparing metal compounds of organic acids.

Another object of the invention is to produce metal salts of high molecular weight organic acids by an improved process which gives a high yield of a product that is relatively free from inorganic salts and aqueous contaminations.

10 A further object is to provide a process which enables one to readily produce metal salts of very weak organic acids and of metals having relatively weak basic characteristics.

An additional object of the invention is to provide a process which avoids the use of aqueous solutions or the presence of water in the production of metal salts of water-insoluble high molecular weight organic acids.

Further objects comprise the production of metal phenates.

The term "organic acids" is used herein to designate acids containing an organic substituent and does not preclude the presence of inorganic components in addition to carbon, hydrogen and oxygen present in all organic acids. The term "high molecular weight organic acids" is intended 20 to designate acids having a molecular weight more than approximately 100.

Example of acids which are to be regarded as organic acids within the meaning of this term, as herein used, and which fall within the 30 broad scope of the present invention comprise substituted acids of phosphorus containing an organic substituent, substituted sulfuric acids, substituted acids of arsenic, phenols, sulfonic acids, carbocyclic carboxylic acids, and aliphatic carboxylic acids. Phenolic compounds are acidic 35 and are within the scope of the invention, as will be apparent from the remaining disclosure.

The following comprise examples of substituted acids of phosphorus which may be used 40 in the present process:

Mono-ester of orthophosphoric acid

Di-ester of orthophosphoric acid

Phosphorous acid

In the above formulae, R may be alkyl, aryl, alkaryl, aralkyl or cyclic non-benzenoid groups.

Similarly, a corresponding series of substituted sulfurous or sulfuric acids or partially esterified sulfur-containing acids, such as sulfuric acid, are contemplated as falling within the broad scope of the invention and the term "organic acids."

Likewise, the term "organic acids" comprehends substituted derivatives of thio acids of phosphorus, such as monothiophosphorous acid, H_3PSO_2 ; dithiophosphorous acid, $\text{H}_2\text{PS}_2\text{O}$; trithiophosphorous acid, H_3PS_3 ; monothiophosphoric acid, H_3PSO_3 ; dithiophosphoric acid, $\text{H}_3\text{PS}_2\text{O}_2$; trithiophosphoric acid, $\text{H}_2\text{PS}_3\text{O}$; tetra-thiophosphoric acid, H_3PS_4 , and the like. By "substituted derivatives of thio acids of phosphorus," it is intended to designate acids containing organic groups of alkyl, aryl, alkaryl, aralkyl or cyclic non-benzenoid types.

Additional examples of organic acids comprise carboxylic acids containing carboyclic nuclei, e. g. aryl, alkaryl, aralkyl or cyclic non-benzenoid types. Examples of such acids comprise phenyl stearic acid, naphthenic acids, naphtholic acids, benzoic acid, and the like. The process is also applicable to high molecular weight aliphatic acids, such as stearic, palmitic, myristic, lauric and oleic acids.

The process of the invention is particularly suited for and finds a most useful application in the preparation of metal salts of water-insoluble phenols. Specific examples of suitable water-insoluble phenols comprise the alkyl phenols such as p-octyl phenol, p-lauryl (dodecyl) phenol and p-cetyl phenol.

It is understood that the process is applicable to the preparation of metal salts of other high molecular weight water-insoluble substituted phenols which contain an aromatic hydroxy group, i. e. an OH group directly connected to a benzene ring, and in which other substituents on the ring may be alkyl, aryl, alkaryl, aralkyl or cyclic non-benzenoid groups. Likewise, polyhydroxy phenols and phenols containing conjugated benzene rings may be utilized as an acid constituent in the formation of the metal salts involved herein. The term "phenols" or "phenolic compound" is used in the present specification and claims to designate, generically, phenols which

are characterized by an acid group comprising one or more OH radicals directly attached to an aromatic nucleus. These phenols or phenolic compounds are represented generically by the type formula:

10

in which M is a metal; v, w, x, y and z are selected from the group consisting of hydrogen, hydrocarbon, oxy and hydroxyl radicals; n is the valence of the metal; and in which the phenolic radical preferably has an alkyl group containing more than four carbon atoms. The hydrocarbon group above mentioned may be an alkyl, aryl, alkaryl, aralkyl or cyclic non-benzenoid group. By the term "oxy radical" hereinabove mentioned, it is intended to designate an hydroxyl group in which the hydrogen has been replaced by sterilification, etherification, neutralization or the like.

As a specific example of a phenol useful in the present process and a method of preparing the same, the following is given:

Phenol and a butene polymer, having an apparent molecular weight of 194 and obtained by polymerization of a mixture of butenes containing butene-1, butene-2, and isobutene, were mixed. To this mixture, containing 237 grams of phenol and 500 grams of the above-mentioned butene polymers, 140 cubic centimeters of 94% sulfuric acid was added slowly with agitation. The temperature was kept below 65° F. during addition of the acid. The mixture was agitated for two hours after the addition of acid was completed and permitted to come to room temperature. The reaction product was then diluted with an equal volume of water and placed in a sealed autoclave where it was heated at 350° F. for an hour with agitation. The product was washed with water, 5% sodium carbonate solution and again with water in order to free it of sulfuric acid, sulfonates and unreacted phenol. A 93% yield of high molecular weight water-insoluble alkyl phenol having an acetyl number of 181 was obtained.

A second example of a method of preparing an alkyl phenol is as follows:

511 grams of crude cresylic acid, 900 grams of an olefin polymer containing an average of 14 carbon atoms per molecule and 475 grams of 98% sulfuric acid were utilized in preparing an alkyl cresol. The ingredients were mixed, the temperature controlled and the product washed as in the previous example. The reaction product was vacuum distilled at 10 millimeters and a 50 to 90% cut separated. This portion of the distillate had a molecular weight of 291 and was used to prepare the calcium salt of the alkyl cresol described in the example hereinafter.

The above methods of preparing the alkyl phenols suitable for the purposes of this invention are merely illustrative. For example, other condensation reactions utilizing alcohols or alkyl chlorides rather than olefins as starting materials may be adopted for introducing an alkyl group into the aromatic nucleus. Also other known condensation agents, such as aluminum chloride, zinc chloride and the like, may be utilized to effect the alkylation of the phenol. A mixture of sulfuric and glacial acetic acids may be used with

advantage as a condensing agent. A suitable mixture comprises 100 parts by weight 98% H_2SO_4 to 60 parts by weight of glacial acetic acid. The presence of the acetic acid facilitates temperature control and gives a softer, easier-handled reaction product.

As has been previously indicated, metal salts of high molecular weight organic acids can be advantageously prepared by directly reacting the acid with a carbide of a metal. Suitable metal carbides are those which react with water to form acetylene.

The following comprise illustrative examples of processes utilizing the principles of this invention for the preparation of monohydroxy phenols:

Example 1.—247 grams of an alkylated phenol having an apparent molecular weight of 247 were agitated for six hours at 500° F. with 64 grams of powdered calcium carbide. A gaseous reaction product containing acetylene was formed and removed. The product remaining in the reaction zone was a dark-colored brittle solid at room temperature and comprised a calcium salt of the alkylated phenol. 94% of the theoretical yield of calcium alkyl phenate was obtained as shown by an analysis of a sample of the reaction product freed from calcium carbide by filtration of its petroleum ether solution.

Example 2.—685 grams of an alkylated phenol having an apparent molecular weight of 290 were agitated for six hours at approximately 500° F. to 540° F. with 90 grams of calcium carbide. A gas containing acetylene was formed and removed. The product remaining in the reaction zone was a dark-colored brittle solid at room temperature. A yield of calcium alkyl phenate, representing 96% of that theoretically possible, was obtained.

The reactions occurring in the examples above disclosed may be represented by the following equation:

In the above equation, R represents an alkyl group but may be aryl, alkaryl, aralkyl or cyclic non-benzenoid groups as heretofore explained. Likewise, the above reaction is applicable to polyhydroxy phenols and to the preparation of phenates of polycyclic phenols in which the benzene rings may or may not be conjugated. The term "phenols" or "phenolic compounds" is therefore used herein to designate generically compounds which contain one or more hydroxyl groups directly attached to an aromatic nucleus.

Metal carbides other than calcium carbide give the above type reaction and may be utilized. Such other compounds comprise those metal carbides which are known to react with water to yield acetylene. These metal carbides are herein termed "acetylides" and comprise the carbides of the alkali metals and alkaline earth metals, namely sodium, potassium, rubidium, cesium, lithium, magnesium, calcium, strontium and barium. To exemplify the reaction of these metal carbides with phenolic compounds generically, the following additional illustrations are given:

Example of reaction with aryl substituted phenols.—p-Phenyl phenol and an excess of ground calcium carbide were heated under nitrogen to between 520° F. and 580° F. for about one-half hour. Rapid evolution of acetylene and tendency to congeal were evidences of reaction. The reaction product was soluble in chloroform. The chloroform-soluble fraction when freed of solvent

analyzed as 9.5% calcium, and upon hydrolysis of the salt 92% of the theoretical amount of p-phenol phenol was recovered.

Example of phenols containing conjugated benzene rings.—A similar reaction to the above was carried out using beta naphthol and an excess of ground calcium carbide. The product was only moderately soluble in chloroform or any other common solvent. A portion of the product was extracted using chloroform and the solvent-free extract contained 10.5% calcium. Upon hydrolysis a 75% recovery of beta naphthol was obtained.

Example of a dihydroxy phenol.—Under conditions substantially the same as in the above, an excess of ground calcium carbide was reacted with 4-p-tertiary butyl catechol. Evidence of reaction was as above described. The product was extracted with chloroform to give a brilliant indigo solution which when freed of solvent analyzed as 8.6% calcium, and upon hydrolysis yielded roughly 80% of an organic substance which gave, upon distillation, 40% of p-tertiary butyl catechol. The product of the reaction is believed to be—

Example of trihydroxy phenol.—Under substantially the same conditions as in all of the above, ground calcium carbide and pyrogallol were reacted. The same evidence of reaction was noted as in the other cases. The reaction product was insoluble in common organic solvents.

Further examples of preparation of calcium salts of various phenolic acids are as follows:

44 grams of p-cyclohexyl phenol and 20 grams of powdered calcium carbide were heated together at 350° F. for one hour. A tan-colored powder was obtained as a product which was insoluble in petroleum ether and soluble in benzene. This product was the calcium salt of the cyclohexyl phenol.

234 grams of an alkyl cresol (molecular weight 291) and 25 grams of powdered calcium carbide were heated at 530° F. with stirring for four hours. The product is a hard brittle solid, soluble in mineral oil, and comprises a calcium salt of the alkyl cresol.

By way of further illustration, a metal salt of a substituted organic acid of phosphorus was prepared by reaction with a metal carbide as follows:

Example 3.—To 267 grams of mono-cetyl phosphoric acid were added slowly and with agitation 100 grams of finely powdered calcium carbide. The temperature was held at 200° F. and the addition of the carbide carefully controlled to avoid excess tendency to foam. The total time for completion of the reaction was one hour. The product was freed of excess calcium carbide by dissolving in diethyl ether, filtering and evaporating off the ether. Analysis for calcium showed complete conversion of the mono-cetyl phosphoric acid to calcium cetyl phosphate.

An example of the preparation of metal salts of carbocyclic carboxylic water-insoluble organic acids is as follows:

Example 4.—To 684 grams of naphthenic acid obtained from a California fuel oil fraction were added 75 grams of powdered calcium carbide. The mixture was heated in a flask with a stirrer

to 350° F. The temperature then rose rapidly due to heat of reaction to 390° F., and the mixture remained at that temperature for some time. The mixture was then allowed to cool to 350° F. and was held at that temperature for two hours. A yield of approximately 90% of calcium naphthenate was obtained and dissolved in a mineral lubricating oil fraction consisting of S. A. E. 30 acid refined Western oil. This solution was filtered to remove unreacted calcium carbide. The calcium naphthenate obtained was soluble in mineral oil in all proportions, and in concentrations of 1 to 2% in oil did not materially increase the viscosity of the oil or cause gel formation. Calcium naphthenate prepared in an aqueous environment is soluble in oil in only comparatively small proportions and causes gel formation when added to lubricating oils in amounts as low as 2%.

Any of the reactions herein disclosed may be carried out in the presence of a non-aqueous, inert solvent such as a hydrocarbon diluent like petroleum naphtha or mineral lubricating oil. The presence of substantial quantities of water in the reaction zone should be avoided. The conditions under which the reaction is carried out may be altered materially, depending upon the time allowed for the reaction and upon the materials being reacted. Atmospheric pressure is preferred but the invention does not preclude the use of either sub-atmospheric or superatmospheric pressures in the reaction zone. The temperature required is a function of the metal carbide utilized and of the organic acid being reacted. Elevated temperatures increase the rate of reaction, and in general, temperatures above 200° F. are preferred, and in the case of the less reactive substituted phenols, such as octyl and cetyl phenols, temperatures above approximately 400° F. are preferred. Intimate contact between the reacting ingredients promote the reaction, and the metal carbide should preferably be added in powdered or granulated form in order that it may be intimately contacted with the organic acid by agitation.

It has been observed that methyl alcohol tends to promote the reaction of calcium carbide with the high molecular weight alkyl phenols, and such an alcohol may be incorporated in the reaction zone.

The process of this invention has a number of advantages. It avoids the use of an aqueous solvent as a medium for effecting the reactions and, as previously noted, thereby precludes difficulties often encountered by reason of impurities or hydrolysis of the reaction product. One could not predict that the high molecular weight water-insoluble phenols, such as cetyl phenol, which are relatively stable and unreactive like hexyl resorcinol, would react with calcium carbide and the like in non-aqueous media. Another advantage of the process is that acetylene rather than water is formed by the reaction of the two initial components and that this gas is easily removed without undue contamination or modification of the finished product. This last feature is of particular utility in that the necessity for removing substantial amounts of reaction products comprising inorganic salts and/or water is avoided. Other advantages of the process will be apparent to those skilled in the art.

In the present specification and claims the term "high molecular weight organic acids" is intended to designate acids having a molecular weight greater than approximately 100, as previ-

ously pointed out hereinbefore. Certain of said high molecular weight organic acids are water-soluble. However, the invention finds a most useful field of application in the preparation of metal salts of high molecular weight water-insoluble organic acids, particularly those of the carbocyclic type. The invention is especially useful with compounds of the phenolic type.

This application is a continuation-in-part of our parent application Serial No. 233,326, filed October 4, 1938, for Methods of preparing metallo-organic compounds. Application Serial No. 233,327, filed October 4, 1938, for Composition of matter and method of preparing the same, is directed to the alkaline earth metal phenate species.

While the character of the invention has been described in detail, and numerous examples of the preparation and application of the process given, this has been done by way of illustration only and with the intention that no limitation should be imposed upon the invention thereby. It will be apparent to those skilled in the art that numerous modifications and variations of the illustrative examples may be effected in the practice of the invention which is of the scope of the claims appended hereto.

We claim:

1. A process of preparing metal salts of phenols which comprises reacting an acetylide with a phenol in an environment substantially free of water, whereby said metal salt is formed in the reaction zone.

2. A process as in claim 1, in which the reaction is carried out in the presence of an inert diluent.

3. A process as in claim 2, in which the reaction is carried out in the presence of a hydrocarbon solvent.

4. A process as in claim 2, in which the reaction is carried out in the presence of methyl alcohol.

5. A process of preparing a metal compound of a phenol which comprises directly reacting magnesium carbide with said phenol in an environment substantially free of water, whereby said metal compound and a gaseous reaction product are formed.

6. A process of preparing a metal compound of a polyhydroxy phenol which comprises directly reacting an acetylide with a polyhydroxy phenol in an environment substantially free of water, whereby said metal compound and a gaseous reaction product are formed.

7. A process of preparing a metal compound of a polynuclear phenol which comprises directly reacting an acetylide with a polynuclear phenol in an environment substantially free of water, whereby said metal compound and a gaseous reaction product are formed.

8. A process of preparing a metal compound of a water-insoluble phenol which comprises directly reacting an acetylide with said phenol in an environment substantially free of water, whereby said metal compound and a gaseous reaction product are formed.

9. A process of preparing a metal compound of a water-insoluble phenol which comprises directly reacting magnesium carbide with said phenol in an environment substantially free of water, whereby said metal compound and a gaseous reaction product are formed.

10. A process of preparing a metal compound of an alkylated phenol which comprises directly reacting magnesium carbide with a water-insolu-

ble carbon-alkylated phenol in an environment substantially free of water, whereby said metal compound and a gaseous reaction product are formed.

11. A process of preparing a metal compound of a water-insoluble acidic organic compound having a reactive hydrogen atom, which comprises reacting an acetylide with said water-insoluble

acidic compound in an environment substantially free of water to replace said reactive hydrogen with the metal of said acetylide and to form a gaseous reaction product comprising acetylene, and recovering the metal compound formed by said reaction.
